UNITED STATES PATENT OFFICE

ARTHUR W. BURKS, OF DECATUR, ILLINOIS

ROTARY PUMP

Application filed June 26, 1930. Serial No. 464,001.

The present invention relates to pumps of the rotary type and more specifically has to do with an improvement upon the pump disclosed and claimed in my co-pending application Serial No. 121,961, filed July 12, 1926.

This pump comprises a casing having a plurality of fluid passages or raceways each provided with an inlet and an outlet, the inlet and outlet of each raceway being spaced apart approximately 180°. In other words, the invention relates to the type of pump in which the water is subjected repeatedly, as it passes through the raceway, to the action of a rotor, but instead of subjecting the water to the action of the rotor for as great a distance as possible around the periphery of the rotor, by locating the inlet and outlet of the raceway adjacent one another, as has heretofore been thought necessary, I shorten the raceway to approximately 180° and utilize the additional space of the complete circle thereby provided for a second raceway. The raceways are preferably disposed in a common plane and are longitudinally curved about a common axis with radii of the same length. Associated with the raceways is a rotor having an annular series of blades forming buckets adapted to traverse the several raceways and propel fluid through each from its inlet to its outlet.

An object of the invention is to provide a pump of this type with improvements which will increase its capacity, both in volume and pressure, without increasing substantially the size of either the rotor or the raceways.

A further object of the invention is to provide a relatively high pressure and high capacity pump of this type which is of extremely simple construction and which will require little or no adjustment or repair over an extended period of use.

Another object of the invention is to improve the construction of the pump from a manufacturing standpoint whereby the parts of the pump may be more economically manufactured and readily assembled.

The invention also has to do with the construction of the various parts. It seeks to provide a raceway section separate and distinct from other sections of the pump where-

by this section may be made from an alloy or relatively hard metal and separately machined. The remaining parts with the exception of the rotor may be cast from comparatively inexpensive metal at a considerably lesser cost.

Still further the invention aims to provide a pump with a self-contained strainer unit which may be readily removed for cleaning or replacement without detaching the strainer carrying section from the pump or disconnecting the pump from the supply or discharge lines.

The invention also aims to provide a unit or section of the pump, preferably cast, which contains one or more pockets adapted to form a liquid air-separating whirlpool at each raceway discharge opening and also contains a supply chamber which serves simultaneously to direct fluid to each raceway inlet opening.

These and other objects of the invention will become clearer as the description proceeds in connection with a preferred embodiment shown in the accompanying drawings wherein,

Figure 1 is a vertical sectional view on the line 1—1 of Figure 2.

Figure 2 is a horizontal sectional view on the line 2—2 of Figure 1.

Figure 3 is a vertical sectional view on the line 3—3 of Figure 1.

Figure 4 is a face view of the section carrying the raceways.

Figure 5 is a face view of the opposite side of the raceway section.

Figure 6 is a horizontal sectional view on the line 6—6 of Figure 3.

Figure 7 is a face view of the rotor.

Figure 8 is a sectional view on the line 8—8 of Figure 4, and

Figure 9 is a sectional view on the line 9—9 of Figure 4.

My Patents 1,619,286, granted March 1, 1927 and 1,686,549, granted October 9, 1928, show pumps of the general type to which the present invention relates and reference to these patents will facilitate an understanding of the mode of operation of the pump constituting the present development.

As explained in these patents the liquid

is propelled through a raceway by a rotor having an annular series of buckets, the rotor and raceway making a substantially watertight seal at the sides of the raceway. Fluid 5 entering the raceway through an inlet opening is engaged by the bucket forming blades on the rotor and the centrifugal force immediately results in a tendency to throw the water against the outer wall of the raceway, 10 the centrifugal force being modified, due to the longitudinally arcuate formation of the raceway and the rotation of the rotor, by a forward or tangential force. The path actually taken by the fluid is a resultant of these 15 two forces. Each amount of fluid operated upon in this manner obtains a great increase in velocity head which is imparted in the form of pressure head to the fluid immediately ahead in the raceway with the result 20 that there is an immediate decrease in velocity head on the part of the amount of fluid which returns to the rotor and is again actuated thereby. In passing through the raceway the fluid follows a helical course i. e., 25 passes repeatedly into and out of the rotor buckets, until it reaches the outlet opening where its very high velocity head is changed to pressure head.

Further description of the functioning and 30 operation of the pump is thought unnecessary with the exception that, as pointed out in the latter patent above mentioned, it has been found desirable to associate with the rotor and preferably at the outlet opening of each 35 raceway, means for maintaining a liquid air-separating whirlpool which engages the buckets as they pass the outlet for the purpose of displacing into the whirlpool fluid contained in the buckets. This displacing 40 action is set up by locating the whirlpool pocket substantially tangential to the path of the buckets so that the liquid of the whirlpool, as it revolves, engages the buckets under the influence of centrifugal force and 45 dislodges the bucket contents into the whirlpool. Any air or gas displaced from the buckets into the whirlpool is immediately separated from the liquid of the whirlpool by the centrifugal action set up.

50 The present pump embodies these features of the invention and increases the capacity of the pump by providing a plurality of raceways adapted to simultaneously receive liquid, independently of one another, and to discharge the same simultaneously. For this purpose each raceway is provided with an inlet and an outlet independent of the inlet and outlet of the other raceway, or raceways, and fluid is propelled through the several raceways by a single annular series of buckets on the rotor.

At each outlet is located a pocket for maintaining a liquid air-separating whirlpool and the two pockets are in communication with 55 the discharge connection. Thus each race-

way separately receives fluid and separately discharges fluid from the pump as distinguished from a multiple stage construction in which fluid which is passed through one raceway returns to a rotor to be propelled 70 through a second raceway.

For producing the pumping action, above generally described, I provide a pump which includes a raceway portion 10, preferably in the form of an independent section of substantially plate-like form (Figs. 4 and 5). On one lateral face are located raceways 11, 12 the former having an inlet opening 13 and an outlet opening 14 and the latter having an inlet opening 15 and an outlet opening 16. 80 The several openings extend through the raceway section to the opposite lateral face and are of somewhat different form. The inlet openings 13 and 15 are narrow and arcuately elongated, being considerably narrower in width than the raceways, which are arcuate both longitudinally and in cross section (Fig. 2). At the forward ends 13', 15' of the inlet openings the back of the raceway plate is beveled so that liquid enters the 90 raceway at a very slight angle to the plane of the raceway.

An outwardly projecting web 17 extends along the radially outer side of each inlet opening to separate the latter from a narrowed extension 18 of each raceway, the extension paralleling the inlet opening and merging with a cut-off 19 extending from each inlet opening to the outlet opening of the other raceway whereby to prevent any 100 substantial portion of the liquid from passing the outlet opening of one raceway and reaching the inlet opening of the other.

Liquid travels through the two raceways in the direction of the arrows 21 and is propelled by means of an annular series of buckets 22 formed on the rotor 23 which is secured to a rotor driving shaft 24. The shaft extends through a stuffing box 25 (Fig. 1) and bearings 26 carried by arms 27 on a rotor 110 housing section 28. The buckets have bottoms 22' curved to conform to the cross sectional curvature of the raceways whereby the wall of the buckets and raceways merge together and form in cross section substantially a complete circle adapted to facilitate the setting up of the helical whirling movement of the fluid as it passes into and out of the buckets in its travel through each raceway. At the radially inner and outer sides of the 115 raceways and of the series of buckets the rotor and raceway section are provided with suitable sealing means such as complementary ribs and grooves 30 which at one or more points 31 (Fig. 4) may have slight notches to permit a small amount of liquid to flow from the raceway into the grooves, thereby reducing the friction between the opposed faces of the rotor and race way section. These notches should be very small so as to permit 120 125 130 135

to flow inwardly only a sufficient amount of liquid to maintain the grooves filled.

The raceway section is formed with a plurality of openings 31 through which project cap screws 32' for the purpose of securing the section to the rotor housing 28 and to a supply section 32 which preferably is formed separately from the raceway section. This is desirable for the reason that the raceway section must be accurately machined, and this work may be done more readily upon a separate independently formed section. Moreover, it has been found that the operation of the pump is more effective if an alloy or other hard metal similar to the metal of the rotor is employed for the raceway portion of the pump, due to the close working fit between the same and the face of the rotor. By separately forming the raceway section, the remainder of the pump such as the rotor housing 28 and the supply section 32 may be cast to exactly, or substantially, final form and need not be accurately machined.

The section 32 has a marginal flange 33 which receives the cap screws 32' thus clamping the raceway section between the sections 28 and 32. The interior of the section 32 provides a chamber 34 in direct communication with each raceway through the inlet openings 13, 15; this chamber is excluded from the outlet openings by means of a second chamber which comprises an upper pocket 36 and a lower pocket 37 disposed respectively at the discharge or outlet openings 14, 16. The pockets are connected by a reduced passage 38 and one of the same, in the present instance the upper pocket 36, communicates directly with the discharge connection 39 which is, therefore, in communication with both pockets of the chamber. The other lower pocket 37 has a drain opening 40 closed by a plug 41.

These pockets serve to maintain adjacent each discharge opening a liquid, air-separating whirlpool adapted to separate air by centrifugal action. The whirling path of the liquid in each chamber is indicated by the arrows W in Figure 6. In order to avoid eddy currents and to permit the liquid of the whirlpool to engage the buckets as they pass the discharge openings, the rear face of each section at the discharge openings has beveled walls 43, these walls forming a considerable portion of the pocket at one side thereof; they serve to direct the liquid of the whirlpool into the buckets as the latter pass the discharge openings. Any air or gaseous fluid contained in the buckets will be displaced into the whirlpool as the liquid of the latter engages the buckets and once in the whirlpool will be separated from the liquid by centrifugal action. The air will pass onwardly through the supply line and during gaseous fluid pumping there will always be maintained in each pocket a suffi-

cient amount of the liquid to displace air or gas from the buckets. Any water from the whirlpool which remains in the buckets after they pass from a discharge opening continues onwardly through the other raceway and is discharged through the outlet opening of the latter.

As will be observed, the discharge connection 39 communicates directly with one pocket 36 and through the latter with the other pockets, so that liquid and air from the lower pocket 37 must travel upwardly through the passage 38 and through the other pocket before it reaches the discharge connection.

The pump section 32 has a supply connection 44 which is in communication with the chamber 34. In the present instance, the supply connection is formed on a separate section 45 having a marginal flange 46 complementary to a flange 32 on section 32, the two flanges having registering threaded openings into which may be inserted cap screws 47. The section 45 serves to close the chamber 34 and carries a screening member 48 of tubular form through the wall of which the entering liquid must pass before it reaches the chamber 34. This screen is disposed at the open bottom 49 of an entrance chamber 50 and has its lower end supported by means of a removable cap 51 which serves to close an opening 52.

The cap 51 has a circular boss 53 tapered so as to clamp the wall of the screen against the edge of the opening 52 and the cap is held in position by means of a supporting plate 54 having one end resting on a ledge 55 and its other end removably secured to the section 45 by means of a cap screw 56. This construction permits the screening element to be removed for cleaning or replacement without separating the pump sections or disturbing the supply line connection. As will be understood, removal of the plate 54 permits the cap plate 51 and screen to drop through the opening 52.

The entrance chamber 50 may have an opening 59 closed by a plug 60 and may also have an opening 61 normally closed by a valve 62. This valve may be opened for the purpose of admitting air to the supply chamber 34, as when the pump is utilized for pumping air to build up air pressure.

For the purpose of supporting the structure a base 62 may be utilized, the same having upstanding bracket arms 63 adapted to cooperate with laterally extending lugs 64 on the rotor housing 28, cap screws 69 serving to secure the section 28 to the bracket arms. The rotor housing 28 thus serves to support the remainder of the pump, since the screws 32 secure the raceway section and the supply section 32 to the rotor housing 28, and the section 32 has secured thereto and supports the supply connection section 45.

The operation of the pump will be clear

from the foregoing description, since the functions of the various parts have been described in connection with the detailed description. Obviously, the construction of the pump may be varied considerably without departing from the invention the essential features of which are set forth in the following claims.

I claim:

- 10 1. In a pump of the class described, a rotor having an annular series of buckets, a plurality of longitudinally arcuate fluid raceways associated with said buckets, each raceway having an inlet and an outlet, a pump section carrying said raceways, a supply chamber having an inlet connection and opening into said raceways through said inlets, and an outlet chamber at each outlet having a discharge connection, said outlet and supply chambers being located in a common pump section and the outlet chambers being connected to one another whereby fluid from one chamber passes through the other to said discharge connection.
- 15 2. In a pump of the class described, a rotor having an annular series of buckets, a plurality of longitudinally arcuate fluid raceways associated with said buckets, each raceway having an inlet and an outlet, a pump section carrying said raceways, a supply chamber having an inlet connection and opening into said raceways through said inlets, and an outlet chamber at each outlet having a discharge connection, said outlet and supply chambers being located in a common pump section separate from said raceway section and the outlet chambers being connected to one another whereby fluid from one chamber passes through the other to said discharge connection.
- 20 3. In a pump of the class described, a rotor having an annular series of buckets, a plurality of longitudinally arcuate fluid raceways associated with said buckets, each raceway having an inlet and an outlet, a pump section carrying said raceways, a supply chamber having an inlet connection and opening into said raceways through said inlets, and an outlet chamber at each outlet having a discharge connection, said outlet and supply chambers being connected to one another whereby fluid from one chamber passes through the other to said discharge connection.
- 25 4. In a pump of the class described, a rotor having an annular series of buckets, a plurality of longitudinally arcuate fluid raceways associated with said buckets, each raceway having an inlet and an outlet, a pump section carrying said raceways, a supply chamber having an inlet connection and opening into said raceways through said inlets, and an outlet chamber at each outlet having a discharge connection, said outlet and supply chambers being located in a common pump section carrying the supply connection for said inlet chamber and serving to close the latter, and a strainer in said last-mentioned section intermediate the supply connection and said chamber, said strainer being removable without disconnection of the chamber section and the strainer carrying section and without disconnecting a supply line.
- 30 5. In a pump of the class described, a rotor having an annular series of buckets, a plurality of longitudinally arcuate fluid raceways associated with said buckets, each raceway having an inlet and an outlet, a pump section carrying said raceways, a supply chamber having an inlet connection and opening into said raceways through said inlets, and an outlet chamber at each outlet having a discharge connection, the outlet chambers being connected to one another whereby fluid from one chamber passes through the other to said discharge connection, said outlet and supply chambers being located in a common section separate from said raceway section, a third pump section carrying the supply connection for said inlet chamber and serving to close the latter, and a strainer in said last-mentioned section intermediate the supply connection and said chamber, said strainer being removable without disconnection of the chamber section and the strainer carrying section and without disconnecting a supply line.
- 35 6. A pump of the class described comprising a rotor, a section having a longitudinally arcuate fluid raceway and formed with a raceway inlet and a raceway outlet extending therethrough, a second section secured to said first-mentioned section and provided with a supply connection, said second section having an interior supply chamber leading through the inlet opening to said raceway and also carrying a discharge chamber at said outlet to receive fluid discharged therethrough from the raceway, and a discharge connection on said second section leading from said discharge chamber.
- 40 7. A pump of the class described comprising a rotor, a substantially plate-like section having a longitudinally arcuate fluid raceway on one face thereof and formed with a raceway inlet and a raceway outlet extending therethrough to the opposite face, a second section secured to said first-mentioned section, said second section having an interior supply chamber leading through the inlet opening to said raceway and also having a discharge chamber at said outlet to receive fluid discharged therethrough from the raceway, a discharge connection on said second section leading from said discharge chamber, and a third section secured to said second

into said raceways through said inlets, and an outlet chamber at each outlet having a discharge connection, the outlet chambers being connected to one another whereby fluid from one chamber passes through the other to said discharge connection, said outlet and supply chambers being located in a common section, a third pump section carrying the supply connection for said inlet chamber and serving to close the latter, and a strainer in said last-mentioned section intermediate the supply connection and said chamber.

5. In a pump of the class described, a rotor having an annular series of buckets, a plurality of longitudinally arcuate fluid raceways associated with said buckets, each raceway having an inlet and an outlet, a pump section carrying said raceways, a supply chamber having an inlet connection and opening into said raceways through said inlets, and an outlet chamber at each outlet having a discharge connection, the outlet chambers being connected to one another whereby fluid from one chamber passes through the other to said discharge connection, said outlet and supply chambers being located in a common section separate from said raceway section, a third pump section carrying the supply connection for said inlet chamber and serving to close the latter, and a strainer in said last-mentioned section intermediate the supply connection and said chamber, said strainer being removable without disconnection of the chamber section and the strainer carrying section and without disconnecting a supply line.

6. A pump of the class described comprising a rotor, a section having a longitudinally arcuate fluid raceway and formed with a raceway inlet and a raceway outlet extending therethrough, a second section secured to said first-mentioned section and provided with a supply connection, said second section having an interior supply chamber leading through the inlet opening to said raceway and also carrying a discharge chamber at said outlet to receive fluid discharged therethrough from the raceway, and a discharge connection on said second section leading from said discharge chamber.

7. A pump of the class described comprising a rotor, a substantially plate-like section having a longitudinally arcuate fluid raceway on one face thereof and formed with a raceway inlet and a raceway outlet extending therethrough to the opposite face, a second section secured to said first-mentioned section, said second section having an interior supply chamber leading through the inlet opening to said raceway and also having a discharge chamber at said outlet to receive fluid discharged therethrough from the raceway, a discharge connection on said second section leading from said discharge chamber, and a third section secured to said second

section and closing one wall thereof, said last-mentioned section carrying a supply connection.

8. A pump of the class described comprising a rotor, a section having a longitudinally arcuate fluid raceway and formed with a raceway inlet and a raceway outlet extending therethrough, a second section secured to said first-mentioned section, said second section having an interior supply chamber leading through the inlet opening to said raceway and also having a discharge chamber at said outlet from said raceway to receive fluid discharged therethrough from the raceway, a discharge connection on said second section leading from said discharge chamber, a third section secured to said second section and closing one wall thereof, said last-mentioned section carrying a supply connection, and a strainer interposed between the supply connection and the said supply chamber.

9. In a pump of the class described, a raceway section having a plurality of longitudinally arcuate raceways at one lateral face thereof, each raceway having an inlet opening and an outlet opening both of which extend through the section to the opposite lateral face, a rotor having a series of buckets adapted to traverse said raceways, and an inlet section secured to said raceway section having a supply connection and disposed at said opposite face, said inlet section having an interior chamber communicating with said supply connection and with said raceways through said inlet openings, and a separate chamber for receiving fluid discharged through said outlet openings.

10. In a pump of the class described, a raceway section having a plurality of longitudinally arcuate raceways at one lateral face thereof, each raceway having an inlet opening and an outlet opening both of which extend through the section to the opposite lateral face, a rotor having a series of buckets adapted to traverse said raceways, and an inlet section secured to said raceway section having a supply connection and disposed at said opposite face, said inlet section having an interior chamber communicating with said supply connection and with said raceways through said inlet openings, and also having a separate chamber for receiving fluid discharged through said outlet openings, said last-mentioned chamber having a discharge opening for a discharge connection and being formed adjacent each raceway outlet with a liquid whirlpool-forming pocket adapted to cause separation of air by centrifugal force.

11. In a pump of the class described, a raceway section having a plurality of longitudinally arcuate raceways at one lateral face thereof, each raceway having an inlet opening and an outlet opening both of which extend through the section to the opposite lateral face, a rotor having a series of buckets

adapted to traverse said raceways, and an inlet section secured to said raceway section having a supply connection and disposed at said opposite face, said inlet section having an interior chamber communicating with said supply connection and with said raceways through said inlet openings, and also having a separate chamber for receiving fluid discharged through said outlet opening, said last-mentioned chamber having a discharge opening for a discharge connection and being formed adjacent each raceway outlet with a liquid whirlpool-forming pocket adapted to separate air by centrifugal force, one pocket communicating through the other with said discharge connection.

In testimony whereof I have hereunto set my hand.

ARTHUR W. BURKS.
